CHUTE CONSTRUCTION FOR SCRAP CIGAR MACHINES

Hjalmar E. Carlson, Brooklyn, N. Y., assignor to International Cigar Machinery Company, a corporation of New Jersey

Application July 25, 1935, Serial No. 33,095

7 Claims. (Cl. 131—38)

This invention relates to improvements in scrap bunch machines, more particularly to an improved chute for delivering the tobacco charge to the funnel which deposits the same upon the chianti belt. The main object of the invention is to divert tobacco from the intermediate portion of the charge passing through the chute for the production of long thin cigar bunches of the so-called panatella shape, or for unusual shapes, for example pipe cigars. To this end the chute is provided with diverging vanes, and by varying the lengths of the vanes the head end or tuck end of the bunch charge deposited on the chianti belt may be provided with any desired quantity of tobacco with respect to the intermediate section of the charge. With this and other objects not specifically mentioned in view the invention consists in certain constructions and combinations hereinafter fully described and 20 then specifically set forth in the claims.

In the accompanying drawing which forms a part of this specification:

Fig. 1 is a side elevation of the improved tobacco feed chute, embodied in a scrap bunch machine of well known type;

Fig. 2 is a partial front view showing of the same.

In carrying the invention into effect there is provided a funnel and a chute arranged to receive a charge of tobacco and deliver it to the funnel, the chute having a vane or vanes which divert portions of the charge to obtain a desired distribution of tobacco in the charge delivered to the funnel. In the best constructions contemplated the funnel guides the tobacco on to the chianti belt of a scrap bunch machine, and a plunger sliding within the funnel acts to compress the charge on the chianti belt to the desired shape. The various means and parts may be widely varied in construction, within the scope of the claims, for the particular construction selected is but one of many possible concrete embodiments thereof. The invention, therefore, is not to be restricted to the specific construction shown and described.

Referring to the drawing, the invention is illustrated in connection with the tobacco feed of the scrap bunch machine disclosed in Patent No. 1,621,088 granted March 15, 1927, on the application of W. H. Schussler and the tobacco may be fed to the scale pan in the same manner by a feed belt (not shown) arranged above the same, as illustrated in said patent. The scale pan drops as soon as the predetermined amount of tobacco has collected therein, and the feed belt is stopped, and the feeding of the tobacco is thereby automatically arrested in the same manner as described in the above mentioned patent.

The scale pan consists of a back wall 11 which is supported by a scale beam (not shown), and a

trough 12 which is hinged on lugs of the wall 11 by pins 13 and normally held against the same by its own weight. The trough may be periodically swung away from the back wall by means of a cam-actuated linkage, disclosed in the above identified patent, which operates an arm 14 carrying a roller 15 engaging a lug 16 of a strap 17 attached to one side of the trough 12. Upon engagement of the roller 15 with said lug the scale pan is opened, thus permitting the charge collected therein to drop into a tobacco chute which forms the subject matter of the present invention. When the roller 15 disengages the lug 16 the trough 12 swings back against the wall 11, the scale pan being thus closed, and the scale 10 pan is returned to its operative weighing position by the scale beam and the feeding of tobacco to the scale pan is automatically resumed by the feed belt.

The above mentioned tobacco chute, into which the collected charge falls, comprises a pair of end walls 18 and 19 adjustably mounted on a bottom plate 20. A pair of clamps 21 and 22 carried by plate 20 engage the projecting ledges 23 and 24 of the end walls 18 and 19 respectively and retain the same on the plate 20. The latter also has a hooked end 25 which is adjustably fastened on a bracket 26 suspended from a member 27 forming a part of the machine frame.

Since the end or side walls 19 which form the side walls of the chute are adjustable relative to each other and to the vanes 28 and 29 in a lateral direction, it is obvious that any desired central or off center arrangement of the vanes relative to the side walls may be produced thereby, further facilitating the feeding of a desired preponderance of tobacco either at one end or the other, of the charge. Indeed, in this manner, it is possible to obtain a similar effect to that which would be obtained if the vanes were moved bodily 30 toward one or the other wall 18 or 19.

Between the walls 18 and 19 the bottom plate 20 is provided with a vane or plurality of vanes which produce the desired distribution or dispersion of the tobacco in the charge. In the construction chosen to illustrate the invention the chute has a short vane 28 and a longer vane 29 which are soldered thereon or made integrally therewith, and flare outwardly to divert tobacco from the mid-section of the charge falling into 45 the chute, to obtain a preponderance of tobacco at one end of the charge. By varying the length of the vanes, the head or tuck end of the charge may be provided with any desired quantity of tobacco with respect to the central section of 50 the charge and thereby obtain various bunch shapes which otherwise would require a wider feed belt, scale pan and chute. Accordingly, cigar bunches of unusual shape such as pipe cigars, or of long thin shape such as panatellas, may be 55 60

readily obtained with a chute equipped with the appropriate set of vanes. By using such vanes the tobacco will be guided to the portions of the bunch charge which requires the most tobacco, thus assuring perfectly shaped bunches. The number, shape and arrangement of the vanes may be varied to best suit the shape of bunch desired, although it will be understood that diverging vanes are preferred. Furthermore, vanes which flare outwardly and downwardly will prevent accumulation of tobacco thereon.

The correctly distributed tobacco falls from the chute into a chamber consisting of end walls 30 and 31 and a swinging gate 32 hinged thereon, the members 30 and 31 being supported on a cross bar 33 carried by a plate 34 of the machine. Swinging motion is periodically imparted to the gate 32 at the proper time by means of a cam-actuated link 35 as will be presently described.

The tobacco is arrested in said chamber at the inlet of a cam-actuated funnel 36, which is periodically lowered to bring its lower end into the bight 37 formed in the chianti belt 38, by a plunger 39 sliding within the funnel. Thereupon the plunger 39 moves upwardly and the gate 32 is swung inwardly to deliver the tobacco charge to the funnel through said inlet, the tobacco dropping through the funnel into the bight 37 of the chianti-belt. The plunger then descends upon the charge so deposited in the bight of the rolling apron and compresses the same to the desired shape and thereafter moves upwardly out of the way with the funnel. Since the construction of the mechanism for actuating the funnel and plunger is well known, further description thereof is deemed unnecessary.

Furthermore, the chamber comprising the walls 30, 31 and the gate 32, although constituting a continuation of the improved chute, is not essential to the present invention and may be omitted if desired.

It is noted that the vanes 28 and 29 are wedge shaped with the point of the wedge up so as to fair into the surface of the chute bottom wall. This prevents hanging up of tobacco scraps on the chute. The vanes are relatively low as compared with the dimensions of the mass dropped from the feed pan 12 so that part of the tobacco flows over the vanes, though a portion of the tobacco is deflected sidewise. Other portions go over, as well as between the vanes, thus eliminating the possibility of lateral gaps in the stream delivered by the chute. It is noted that the feed pan 12 is relatively narrower with respect to the chute 18, 19, 20 and moreover that this feed pan is of fixed width as compared with the adjustable width of the chute. Thus, when adjusting the bunch machine for different lengths of bunch, the fixed width of the feed pan 12 constitutes a limiting factor on the length of bunches which can be produced in the machine. By using the distributing vanes 28 and 29, as disclosed, this limitation on machines in which the tobacco is delivered from pans or belts of fixed width is obviated.

What is claimed is:

1. In a scrap bunch machine, the combination with a funnel, of a chute arranged to receive a charge of scrap tobacco and deliver it into said funnel, said chute being provided intermediate its sides with diverging vanes which spread the charge to obtain a preponderance of tobacco at one end of the charge delivered to said funnel.
2. In a scrap bunch machine, the combination with a funnel of an inclined chute arranged to

receive a charge of tobacco and deliver it into said funnel, said chute being provided with a single pair of diverging downwardly flared vanes of different length which divert portions of the charge towards the sides of the chute to obtain a preponderance of tobacco at one end of the charge delivered to the funnel.

3. In a scrap bunch machine, the combination with a funnel, of an inclined chute arranged to receive a charge of scrap tobacco and deliver it into said funnel, said chute being provided intermediate its sides with a vane which is constructed and arranged to permit the tobacco to flow to either side thereof and diverts a portion of the charge to obtain a preponderance of tobacco at one end of the charge delivered to said funnel.

4. In a scrap bunch cigar machine, the combination with a funnel for receiving a supply of tobacco from which cigar bunches are to be formed, of a chute arranged to deliver tobacco into said funnel, said chute having an inclined bottom surface and opposed side walls for retaining the tobacco on and directing the same along said surface, a vane extending diagonally in said chute intermediate said side walls for spreading the tobacco in said chute, and means for relatively adjusting said side walls and vane, said vane being secured to said bottom surface and extending generally lengthwise of said chute, said vane being of a wedge-shaped contour of increasing height above the chute from the upper to the lower ends of the vane to prevent hanging up of tobacco pieces on said upper end.

5. In a scrap bunch machine, the combination with bunch forming and rolling mechanism, of means for intermittently delivering a stream of filler tobacco to said mechanism sufficient for the formation of a cigar bunch, and relatively adjustable members intermediate said means and mechanism for diverting portions of said stream outwardly to create a preponderance of tobacco at one end of the bunches produced by said mechanism.

6. In a scrap bunch cigar machine, the combination with a chianti belt for rolling the cigar bunch, of a device for intermittently delivering increments of tobacco of an approximately predetermined width, means including a funnel for directing tobacco into said chianti belt, a chute for receiving said increments from said device and delivering them into said means, and mechanism in said chute comprising downwardly and outwardly directed vanes of such height and so constructed and arranged that part of the tobacco from said device will flow over said vanes and part will be diverted sidewise to provide a stream of tobacco having a width substantially greater than that delivered by said device.

7. In a scrap bunch cigar machine, the combination with a chianti belt for rolling the cigar bunch, of a device for intermittently delivering increments of tobacco of an approximately predetermined width, means including a funnel for directing tobacco into said chianti belt, a chute for receiving said increments from said device and delivering them into said means, and mechanism in said chute comprising downwardly and outwardly directed vanes diverging in opposite directions and of such height and so constructed and arranged that part of the tobacco from said device will flow over said vanes and part will be diverted sidewise to provide a stream of tobacco having a width substantially greater than that delivered by said device.
